UNITED STATES PATENT OFFICE.

FRANK J. WATERS, OF PROVIDENCE, RHODE ISLAND, ASSIGNEE TO WATERS ENGINE COMPANY, OF SACO, MAINE, A CORPORATION OF MAINE.

FEED-MOTION DEVICE.

No. 926,915.

Specification of Letters Patent.

Patented July 6, 1909.

Application filed February 24, 1908. Serial No. 417,510.

To all whom it may concern:

Be it known that I, FRANK J. WATERS, a citizen of the United States, residing at Providence, in the county of Providence and State of Rhode Island, have invented certain new and useful Improvements in Feed-Motion Devices, of which the following is a specification, reference being had therein to the accompanying drawings.

Like reference numerals indicate like parts.

Figure 1 is a top plan view of my improved feed motion device in combination with the cylinder of a steam engine and an oil pump to lubricate said cylinder. Fig. 2 is a front elevation of said feed motion device, the wheel and shaft being shown in central longitudinal section on a line at a right angle to said shaft. Fig. 3 is a front elevation of said feed motion device and an end elevation of the steam cylinder, together with the means of adjusting the length of the stroke of said device. Fig. 4 is a view partly in elevation and partly in section as seen on line $x-x$ of Fig. 3. Fig. 5 is a view partly in elevation and partly in section as seen on line $z-z$ of Fig. 3. Figs. 6 and 7 are detail views illustrating the means of securing respective ends of the friction strap. Figs. 4, 6 and 7 are on an enlarged scale.

My invention relates to a mechanical device for converting a continuous rotary motion into a reciprocating motion, and is a substitute for the rack and gear commonly used for that purpose.

My invention consists of the novel construction and combination of the several parts hereinafter described, as set forth in the claim.

In Fig. 1 my said feed motion mechanism is shown as operated by the shaft of a steam cylinder of a rotary engine for the purpose of pumping oil into said cylinder to lubricate the interior surface thereof for the movements of a rotary piston blade therein. It is obvious, however, that said invention is also applicable for various mechanical purposes in machines where it is desired to convert a rotary movement, whether continuous or intermittent, into a reciprocating movement.

In the drawings 1 represents the cylinder of a rotary steam engine. The cylinder has the usual head 2 and the bearing and stuffing

box 3. A rotatable shaft 4 is mounted in the bearing 3 and extends out from said bearing, as illustrated in Fig. 1.

A bracket 5 is secured by bolts 6 to the cylinder head 2 and a bracket 7 is secured to the cylinder 1 by bolts 8. The brackets 5 and 7 support, respectively, the bearings 9 and 10. A shaft 11 is rotatably mounted in the bearings 9 and 10. At one end of the shaft 11 is fastened a disk 12, having a diametrical slot. An oil tank 13 is mounted on a proper fixed support and has an oil supply pipe 14. The piston rod 15 of an oil pump is provided with a pin 16, which projects from said piston rod. The pin 16 projects loosely into the diametrical slot of the disk 12. The rotation of the shaft 11 in the direction indicated by the arrow 17 causes the rotation of the disk which is mounted on said shaft and imparts a reciprocating movement to the piston rod 15, thus pumping oil from the tank 13 into the cylinder 1 to lubricate the interior surface of said cylinder for the movement of the rotating piston blade therein.

A circular disk 18 has a central hub 19, through which the cylinder shaft 4 passes and said shaft is secured to said hub by the spline 20. The disk 18 has the radial slot 21.

A bracket 22 extends from the disk 18, which is provided with two parallel sides 23, a bearing 24 and a cross piece 25. A screw 26 has a head 27. The central portion of the shank of the screw 26 is threaded but the portions 28, 29, are smooth and cylindrical in the smooth bores of the bearing 24 and of the cross piece 25. A nut 30 and washer 31 are mounted on the end of the screw 26 opposite to the head 27.

A block 32, rectangular in vertical and horizontal sections, has a screw-threaded bore, by which it is adjustably mounted on the screw 26. This block 32 has a pin 33, whose outer end is threaded for the reception of a nut 34. A flanged tube or bearing 35 is loosely mounted on the pin 33 and a link bar 36 is mounted on said tube 35. The block 32 is accessible through the opening 21 in the disk 18.

My improved feed motion device is provided with a circular disk or wheel 37, having the peripheral flange 38, which is made with a circumferential groove 39 as shown in detail in Fig. 5. The circular disk or wheel 37 has

a central hub 40, whose bore fits upon the end of the shaft 11 and is fastened thereto by a spline 41. A friction strap 42, preferably of steel, loosely surrounds the said disk or wheel in the circumferential groove or channel 39 of the flange 38 thereof.

A strap holder 43 has a curved concave surface adapting it to a sliding fit upon the periphery of the wheel or disk 37. One end 10 of the strap 42 is fastened to the strap holder 43. The strap holder 43 has two ear pieces 44. A pin or pivot 45 connects a lever arm 46 with the ear pieces 44.

A link 47 has two parallel sides 48 and two 15 oppositely-arranged tubular bearings 49, 49. A pivot 50 passes through the two bearings 49 and mounts the said link 47, 48, upon the lever arm 46 out beyond the pivotal mounting 45 of said lever arm. The link 47 is fastened to one end of the strap 42. A lever 51 has a bearing 52 and a pivot 53 extends through the bearing 52 and also through two bearings 54, 54, which are formed on the respective sides 48, 48, of the link 47. Near 25 the outer end of the lever 51 it is tapped to receive a screw 55, whose inner end bears against the end of the link 47.

The inner end of the lever 51 has a transverse nick or notch 56 (Fig. 7), in which one 30 end of a curved spring 57 is inserted. The upper end of the spring 57 is curved for a wearing surface and bears against the edge of the lever arm 46, being held from lateral displacement thereon by the guide plates 58, 35 which are secured to the lever arm 46 near the end thereof.

The upper end of the lever arm 46 is connected by the pivot 59 to the end of the link bar 36.

40 The outer end of the shaft 11 is mounted in bearings which are formed on the bracket 60, the latter being held to a fixed support by bolts 61. Said bracket also supports a hanger 62, at the lower end of which is a tubular block 63. The outer end of the bore of block 63 is threaded to receive and engage the tubular nut 64, whose exterior and interior surfaces are threaded. A brake shoe 65 is curved to fit the curved edges of the flanges 50 38 of the disk or wheel 37 and is provided with a cylindrical stem 66 and a screw 67, both integral. A check nut 68 on the outer end of the tubular nut 64 holds the said nut 64 in its adjusted position. A spiral spring 55 69, surrounding the smooth cylindrical portion of the screw 67, has one end bearing against the lower end of the stem 66 and its opposite end bearing against the inner end of the tubular nut 64.

60 The operation of my said feed motion device is as follows: The purpose of the mechanism illustrated in the drawings and hereinbefore specifically described is to convert the continuous rotary motion of the shaft 4 into 65 an intermittent rotary movement of the

shaft 11, and the particular work accomplished in the operation of the device as so illustrated and specified is to utilize the rotation of the shaft 4 of the cylinder 1 to periodically pump oil from the oil tank 13 into said cylinder for the proper lubrication of the interior peripheral surfaces of said cylinder to allow the free rotational sliding of the piston blades therein, constituting a portion of a rotary steam engine. Supposing the direction 75 of the rotation of the shaft 4 to be as indicated by the arrow 70 in Fig. 3, said shaft during one-half of its rotation will communicate a movement to the lever arm 46 in the direction indicated in said figure by the arrow 80 71, and during the other half of its rotation it will communicate a movement to the lever arm 46 in the direction indicated in Fig. 2 by the arrow 72. Such alternation of movement of the lever arm 46 is due to the 85 fact that the link bar 36, which is pivotally connected at 59 to the lever arm 46, is mounted eccentrically to the shaft 4. The length of each stroke of the lever arm 46 is determined by the amount of eccentricity of 90 the position of the nut or block 32 on the screw 26, the nearer the nut or block 32 is to the axial line of the shaft 4 the shorter will be the stroke and vice versa, and the length of said stroke is therefore adjustably 95 determined and regulated by turning the screw 26 by its head 27, thus causing a corresponding travel of the nut or block 32 on said screw.

When the lever arm 46 is oscillated by the 100 link bar 36 in the direction indicated by the arrow 71 in Fig. 3, the strap 42 is tight on the periphery of the disk or wheel 37 and compels said disk or wheel to rotate in the direction indicated by the arrow 73, thereby imparting an equal degree of rotation to the shaft 11 to which it is keyed at 41. The intermittent rotation of the shaft 11, thus caused in the direction indicated by the arrow 17 105 in Fig. 1, results, by means of the slotted 110 head 12 and the pin 16 of the piston rod 15, in an intermittent action of the oil pump and injects oil periodically into the cylinder 1. When said oscillation of the lever arm 46 in that direction reaches its limit and is reversed, as represented in Fig. 2, the strap 42 is loose on the disk or wheel 37 and slides thereon, without imparting any movement to said wheel or disk, the latter being prevented from such movement by the brake 115 shoe 65, which is pressed up into engagement with the peripheral edges of the flanges 38 by means of the spiral spring 69 bearing against the stem 66 of the brake shoe 65. Said pressure of the brake shoe though sufficient 120 to hold the wheel or disk 37 from movement caused by the slight sliding friction of the strap 42 thereon when the movement is in the direction indicated by the arrow 72 in Fig. 2, is not sufficient to prevent the move- 125 130

ment of the wheel or disk 37 when the movement is in the direction indicated by the arrows 71 and 73 in Fig. 3.

The reason why the strap 42 is loose on the wheel or disk 37, when the movement is in the direction indicated in Fig. 2 by the arrow 72, is that the leverage of the arm 46, so far as the pivot 45 is considered as the fulcrum, causes the link 47, 48 to push the end of the strap 42, there connected to it, away from the opposite end of said strap; and at the same time, so far as the pivot 50 is considered as a fulcrum, the arm 46 pushes by means of the pivot 45 the ears 44 and the strap holder 43, which is fastened to said opposite end of the strap 42 in a direction opposite to that indicated by the arrow 72. Thus the strap 42 does not hug so tightly the rim of the disk or wheel 37 and loses its frictional hold thereon. But when the movement of the lever arm 46 is in the direction indicated by the arrow 71 in Fig. 3, the leverage of the arm 46, so far as the pivot 45 is considered as the fulcrum, draws the link 47, 48 in the direction indicated by the arrow 71 and so pulls the end of the strap 42, there connected to said link, toward the opposite end of the strap 42; and at the same time, so far as the pivot 50 is considered as a fulcrum, the arm 46 by the pivot 45 moves the ears 44 and the strap holder 43, to which the said opposite end of the strap 42 is fastened, in a direction opposite to that indicated by the arrow 71, thus tightening the frictional hold of the strap 42 on the rim of the wheel or disk 37. This tight frictional hold or bite of the said strap on the wheel or disk overcomes the pressure of the brake shoe 65 on the rim of the wheel or disk and compels the wheel or disk to rotate as shown by the arrow 73. The degree of the tightness of said frictional engagement of the strap 42 on the periphery of the wheel or disk 37 can be regulated and adjusted by means of the spring 57 and the lever 51. When the screw 55 is tightened up it elevates the outer end of the lever 51 and consequently moves the inner end of said lever nearer to the arm 46. This movement of the lever 51 flattens somewhat the bow spring 57 and thus increases its tension thereby causing the free end of said spring to bear with greater force against the edge of the arm 46. The spring 57 therefore reacts and presses the lever 51 and the screw 55 so that the latter bears with increased power upon the link 47, and the link 47 consequently holds the portion of the strap 42 contiguous thereto in an increased friction upon the rim of the wheel or disk 37. But if the screw 55 is loosened, the outer end of the lever 51 is lowered, and

the inner end of said lever is moved away from the arm 46 and the tension of the spring 57 is relaxed, so that the link 47 bears with less force on the contiguous end of the strap 42. In this manner, the exact length of the feed motion imparted by the friction strap 42 to the wheel or disk 37 can be regulated, determined and maintained, thus making this device capable of very fine and exact work, such as cannot be accomplished by a mere rack-and-gear feed mechanism. When the screw 55 is loosened or withdrawn, the resilience of the strap 42 causes said strap to loosen its frictional hold upon the periphery of the wheel or disk 37, and by means of the link 47, fastened to said strap, draws the arm 46 out of the position illustrated in Fig. 2, slightly to the right of said position; but when, by tightening up the screw 55, the outer end of the lever 51 is elevated, the upper end of the spring 57 presses the upper end of the arm 46 back into alignment with the ears 44, as shown in said figure. The arm 46 then, slightly turning on the pivot 45 as a fulcrum, causes the link 47 to pull the strap 42, there connected with said link, thus increasing the frictional hold of the strap 42 on the rim of the wheel or disk 37.

In order to give a reverse direction to the feeding device, the parts 36 and 42 to 59, both inclusive can be changed 180° in position upon and with reference to the wheel or disk 37, thus making the device operable in either one of the two opposite directions as may be desired. This feature is believed to be a useful novelty in the art.

I claim as a novel and useful invention and desire to secure by Letters Patent:—

The combination of a circular disk rotatably mounted on a support; a friction strap 100 engageable with the periphery of said disk; a strap holder having ears and slidable on said periphery and fastened to one end of said strap; a lever arm; a pivot connecting said ears to the lever arm; a link pivotally mounted at one end on the lever arm and fastened at its other end to the other end of the strap; a lever centrally pivoted to said link; a screw passing through the outer end of said lever and bearing thrustwise against 110 said link; and a bow spring secured at one end to the rear end of said lever and having its opposite end in sliding loose bearing contact with said lever arm.

In testimony whereof I affix my signature 115 in presence of two witnesses.

FRANK J. WATERS.
